(57) **CLAIM**

The ornamental design for an image capture and analysis device, as shown and described.

DESCRIPTION

FIG. 1 is a front view of an image capture and analysis device showing our new design;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a front and right side perspective view thereof.

The broken lines depict portions of the image capture and analysis device in which the design is embodied that form no part of the claimed design.

1 Claim, 7 Drawing Sheets
